HYDRO-PNEUMATIC BUCKET CLEANER

Augustus J. Penote, Shaker Heights, Ohio

Application April 30, 1932, Serial No. 608,429

8 Claims. (Cl. 198—144)

My invention relates to hydro-pneumatic bucket cleaners, and more especially to cleaning devices for cleaning the moving buckets mounted upon power driven excavating machines, whether of the wheel or ladder type. For purposes of illustration, I have illustrated my bucket cleaners as applied to an excavator in which the excavating is accomplished by an endless series of buckets which are caused to travel up and down a boom by means of sprocket chains or other endless members, so that the buckets are filled while moving upward against the end wall of the trench, and in which each bucket is intended to discharge its load when turned upside down in the upper end of its path of travel, my improvement providing means for continuously discharging the contents of each bucket as it reaches its highest point of travel, as above stated.

My cleaner is pivoted on one or more levers which are pivotally mounted on an horizontal axis, the cleaner mechanism removing the contents of each bucket as the latter passes said uppermost position.

One of the objects of my invention is to provide an excavating machine with continuously and effectively operating means for discharging the contents of each bucket as it reaches the uppermost point in its path of travel, and to so cause the bucket discharging means to function without possibility of damage to the machine due to breakage of parts of the discharge mechanism because of failure of obstructions such as stones and similar obstacles to clear the passage through which the buckets are intended to pass in their normal continuous travel.

A still further object of my improvement lies in the provision of special mechanism for yielding to the undue strain to which the buckets are subjected when such obstacles are presented as before explained, and still have the inherent capacity of returning to their normal relation and position of parts after such obstacles are removed. This particular object for providing such yielding mechanism is attained by employing for the present yielding means, as a substitute for almost universally used spring coils and other metallic yielding devices which are found to be so susceptible to breakage when subjected to the strain required, a hydro-pneumatic means having much less liability to fracture when used in the more than ordinarily rough manner required in the excavating service for which such heavy machines are intended.

With the above and other objects in view, my

invention consists in the novel features of construction and arrangement of parts to be hereinafter more fully described, claimed and illustrated in the accompanying drawings, in which,

Figure 1 is a fragmentary side elevation of an excavating machine provided with my improved bucket and cleaner mechanism, including my novel hydro-pneumatic yielding device;

Figure 2 is a central vertical section of the upper portion of the elevator of an excavator together with the supporting boom and a cleaner mechanism for the buckets, the section being taken in the plane indicated by the line 2—2 of Fig. 3;

Figure 3 is a detail transverse section taken in the plane indicated by the line 3—3 of Fig. 2;

Figure 4 is a central vertical section of the upper portion of the elevator of an excavator together with the supporting boom and a modified form of hydro-pneumatic yielding mechanism for the bucket cleaning mechanism, the section being taken in the plane indicated by the line 4—4 of Fig. 5;

Figure 5 is a fragmentary plan view of the upper portion of the elevator and cleaning mechanism combined with the modified form of yielding device;

Figure 6 is a detail section taken in the plane indicated by the line 6—6 of Fig. 4, and

Figure 7 is a detail section of the air vent taken in the plane indicated by the line 7—7 of Fig. 4.

My machine frame 5 is mounted upon a supporting carriage 6 and will include a motor 7, supporting masts 8 having mounted thereon by means of a cross shaft 11, a rearwardly extending boom 9 over which endless carriers 10 travel.

Cable mechanism 12 and motor actuated reel 13 may swing the boom on shaft 11. A series of buckets 14 carried by the chains 10 present a cutting edge 15 toward the trench wall as they rise on the lower side of the boom. A pair of sprocket wheels 16 is mounted upon the shaft 11, and another pair similarly mounted at the lower end of the boom 9, these sprockets providing rotatable

mounting for the chains, and the shaft 11 furnishing driving power for the bucket chains through suitable gearing 17. The buckets 14 are of well constructed and are secured to certain links of the chains 10 at suitably spaced

intervals and each bucket has its front end open and is tapered at its rear end, the carrier chains 10 being spaced apart. As the buckets travel upwardly and move over and around the upper sprocket wheels 16, the rear ends 18 of the buckets

are tilted away from the chains, so as to bring the inner sides downward, discharging the load. While each bucket is traveling upward however, the position thereof is such that it will carry the 5 load. The upper end of the boom 9 has brackets 19 suitably secured thereto as by similar fasteners 20, the upper ends of the brackets providing suitable bearings 21 for the cross shaft 11.

The cleaning mechanism used in my construction 10 comprises a cleaner member 23 having a curved form as seen in side elevation, with the lower end of the arc pivoted at 24 to the bracket 19 at a point somewhat beneath the main shaft 11, so that the arc is positioned in enclosing relation 15 to such shaft. The opposite end of the member 23 is extended in a substantial tangent to said arc to provide an elongated cleaner arm 25 which is provided at its outer end 26 with a scraper plate or blade 27 whose function is to 20 dislodge the contents of each bucket 14 successively, as the latter travel with the chains 10 over the sprockets 16. The front end of each bucket adjacent its cutting edge 15, is open and thereby permits the curved scraper 27 to enter 25 the bucket and pass through the same from front to rear, during the dumping operation, as the parts are shown in relative position in Figs. 2 and 4 of the drawings.

By mounting the cleaner member at 24 beneath 30 the shaft 11, the curved edge of the plate 27 will be made to approach very closely the bottom of each bucket 14 when the latter has tilted into discharging position as before explained.

The relative position of the centers 11 and 24 which mark the radii of the curves or arcs determining 35 the paths of movement of the buckets 14 and scraper blades 27, respectively, serves not only to establish the path of movement of the bucket in the arc 28, shown clearly in Figs. 2 and 4 as the outer arc, and the movement of the scraper blade in the arc 29, the two arcs gradually separating as the emptied buckets travel downward on the upper or outer side of the boom 9; but such established positions of the arcual centers 40 very positively move the said blades 27 on the arm 25 in close proximity to the bucket inner surface when the desired scraping action is most desired and at the proper position of the bucket for discharge of its contents, and also resulting in a 45 gradual separation of the parts as the latter swing on their spaced pivots.

Since the buckets 14 are carried continuously on the endless chains 10, and the scraper blade 27 is mounted on the brackets 19 as a relatively 50 stationary element for cleaning each bucket as the latter travels over the blade, it is found expedient to provide a means for permitting the scraper blade to yield, when the resistance encountered by the scraper member is so great that 55 great danger exists of fracture of parts, if the mounting of the cleaner arm were positive and unyielding. Such abnormal resistance to the cleaner action of the blade 27 to the bucket 14 may be due to the general character of the material being excavated, or may be due to the presence 60 of metallic articles or stone carried up in the buckets until the discharging point of the carrier is reached, and the obstacle is too large to pass through the bucket.

It has not been found desirable to mount the cleaner arm to yield too readily to the encountered 65 obstruction in the bucket, since it is well to operate the cleaner with as great force as it can exert.

While I have not provided in my yielding mech-

anism for the cleaner arm 25, a positively actuating mechanism for moving the scraper blade 27 through the buckets, I have found it particularly practicable to mount the cleaner member to yield to obstruction within the buckets by two 80 wholly different and dissimilar means of presenting the cleaner blade to the load to be discharged. One of these yielding devices comprises the mounting of the bucket carriers and the cleaner arms on spaced centers, so that as 85 the obstruction presents greater resistance to removal, the blade 27 will yield on its pivot and also travel at a gradually greater distance from the bucket. Another yielding means for the cleaner arm has been found to be highly advantageous, 90 the same consisting of a hydro-pneumatic resistance mechanism which I have found well adapted for mounting upon the boom, and providing suitable actuating connections between a piston working in a hydraulic drum and the said 95 arm. I am therefore able to provide a plural yielding means for the cleaner.

My hydro-pneumatic mechanism for yieldingly holding the cleaner blade 27 in normal and stationary position, is preferably formed of two 100 drums of elongated form which are in a substantially common plane with the boom 9 and the carrier chains, and spaced from the ends of the boom. The lower ends of the drums will have a substantially common bottom, and one or more 105 openings leading from the lower end of one drum to that of the other. The lower ends of the drums will normally hold a suitable liquid, such as oil, and one of the drums fitted with a suitable pressure gauge.

In my preferred form, I have shown in Figs. 2 and 3, the two drums mounted one within the other, the inner drum 22 mounted in spaced relation from the outer drum and eccentric thereof. A common bottom 34 supports the two drums 115 which also have their tops in a substantially common plane.

In the drum 22 a piston 30 is mounted for reciprocation, so that the lower end of the drum containing the liquid 31 which is permitted to 120 flow through the openings 32 in such lower end into the outer drum 33, may resist the downward thrust of said piston. The latter is mounted upon a piston rod 35 which is longitudinally movable through the apertured closure 36 which is 125 provided with suitable stuffing box structure 37 for the purpose. The upper end of the rod 35 is connected by the yoke 38 with the pivoted cleaner member 23 by the pin 39, so that yielding of the scraper blade 27 to an obstruction in the bucket 130 14 will force the piston rod 35 and the piston 30 downward against the liquid 31 in the drum 22 and so force the liquid through the said lateral openings 32 out into the outer drum 33. The combined drums 22 and 33 are mounted for 135 slight swinging motion upon a substantially horizontal transverse pivot pin 40 supported at its ends upon frame members 41 which are mounted fixedly at their ends upon the boom structure 9. The common bottom 34 has an attached sleeve 42 enclosing the said stationary pin 40 thereby providing means for rocking the drums as a unit upon the pin 40.

The outer drum 33 is provided as a compression chamber whose upper portion will be filled with air, and the upper end 43 will be provided with an air valve 44 for loading, so that the air chamber 45 will yieldingly resist the inflow of liquid from the openings 32, as the piston 30 descends in the drum 22 in yielding to the rearward movement 140

of the scraper blade 27. The piston 30 will therefore be resisted in its descent by the restricted openings 32 and by the air compressed in the chamber 45 by the inflowing liquid from the inner drum 22. Above the piston 30, the drum 22 is provided with an air release valve 46 of conventional design to permit escape of air from the drum by increased internal pressure, but preventing entrance of air from the outside under normal pressure. This permits escape of air on the up-stroke of the piston.

As the piston 30 reciprocates in the drum 22, the yoke member 38 swings laterally slightly as shown in Fig. 2 of the drawings, but which movement is in reality, in a plane in the direction of the advancement of the machine, as a result of the pivot pin 39 slightly approaching and receding from the cross shaft 11. Such swinging of the yoke and the rod 35 attached thereto produces a corresponding rocking movement of the connected drums 22 and 33 on the pivot, as above explained. This provision of the rod 35 and yoke 38 with a common axis avoids the otherwise essential connection of the piston rod with the pin 39 by a separate link member, as will be obvious. The position of the yoke member and cleaner member 23 when the scraper blade 27 is in its extreme rearward or withdrawn position of movement in the bucket, is shown in dotted lines in Fig. 2.

The cleaner member 23 is operated as a lever of the third class, the resistance being encountered where the scraper blade 27 engages the material being discharged from the buckets, and when such blade has receded from the full line position shown, gases before compressed in the chamber 45 by a former down stroke of the piston, will force the liquid back through the openings 32, raising the piston and swinging the cleaner arm 25 and its blade 27 back to its normal position of impact for discharging the material in the bucket.

In the last four views of the drawings, I have illustrated an alternative form of hydro-pneumatic yielding mechanism and its connection with the cleaner member 23, this modified mechanism including two elongated drums 47 and 50 mounted side by side in a common plane with the boom 9, the drum 50 being relatively longer, while the lower ends of the drums will have a substantially common bottom, and the side walls of the drums being very slightly spaced apart. The upper end of drum 50 is provided with the conventional loading valve 71.

The two drums of the modified form will be mounted fixedly in the boom, parallel spaced guide bars 48 being provided in a plane at right angles to the common plane of the drums and carriers, and also parallel to the piston rod 49. These guide bars have guide slots 51 in which the ends of a transverse connecting pin 52 travel, this pin engages the transverse opening 53 in the piston rod and the openings 54 in the forked ends 55 of a connecting link 56, certain guide blocks 57 suitably spacing the outer surfaces of the fork from the walls of the slots 51. A suitable L bracket 58 serves to support the bars 48 upon the drum 50 which in turn is supported upon the main boom structure 9.

In the drum 47 the piston 59 reciprocates which is mounted upon the piston rod 49, which latter is longitudinally movable through the apertured closure 60. The link 56 is pivoted to the cleaner member 23 by a fork engaging the pin 61. The lower ends of drums 47 and 50 will normally hold

a suitable liquid such as oil, and an L-shaped channel 62 leads from the drum 47 into the bottom of the drum 50, said channel being provided with a drain plug 63, and the drum 50 fitted with a suitable pressure gauge 64. The operation of the piston 59, and the consequent pressure exerted against the liquid to force the same through the restricted channel 62 into the drum 50, is very similar to that of the piston 30 and the flow of liquid through the openings 32 into the outer drum 33, of the preferred form.

Above the piston 59, the drum 47 is provided with an air release valve 65 comprising a ball 66 normally yieldingly pressed against the valve seat 67 by the coil spring 68 detachably mounted outside the wall of the drum and secured therein by suitable plug 69. A lateral aperture 70 permits escape of air from the enclosing tube, and the coil will yield to outward pressure, when the piston 59 rises in response to the lifting force of the liquid, as the blade 27 returns to its normal position of impact.

The operation of my improved hydro-pneumatic bucket cleaner as above described is unique and effective. This is due in great part to the greatly desired pivoting of the member 23 at the point 24 almost directly beneath the cross shaft 11. This arrangement makes feasible the pivoting of the fork 38 or link 56 at 61, between the outer end 26 and the fulcrum 24, thereby effecting a yielding movement of the scraper 27 by a much shorter stroke of the piston and its rod, than would otherwise be possible, though my improved pneumatic resistance pump would suffer less from extreme length of stroke, than would a coil spring heretofore made use of for permitting yielding movement of the scraper responsive to undue strain by abnormal obstacles in the bucket contents.

The distance travelled by the pivot 40 is obviously only about half the distance yielded by the blade 27 when an abnormal load is encountered, and for the same reason, the return stroke of the scraper to normal position is equally positive, rapid and effective. To accomplish such efficient mechanical operation of the device, I have formed my cleaner member 23 as an approximate arc of 180 degrees operating as an encircling rim or hook swinging about the shaft 11, and thereby permitting the fulcrum pivot 24 below such shaft while the scraper 27 is quite out of alignment with any two of the points 11, 24 and 39. Any yielding movement of the scraper therefore, results in the recession of the member 23 from the shaft 11.

The pressure of the material contained within the moving bucket tends to rock the cleaner 23 counterclockwise as seen in Fig. 2, on its fulcrum 24, thereby forcing the piston 30 downward in the drum 22, raising the level of the liquid 31 in the drum 33, and correspondingly compressing the air 43. This compression will exert a continuous upward thrust of the piston until relieved.

It is evident that suitable conveyor mechanism will be needed for receiving material dumped from the buckets while the latter are in the position indicated in Figs. 2 and 4 of the drawings, but since this invention is not especially concerned with the type of such mechanism to be employed for this purpose, it has not been illustrated nor described in detail. It is to be understood that the digging mechanism will be driven from the shaft 11, but the particular driving connection between the said shaft and the motor to be employed is not shown, other than the embodiment in part of the gearing 17.

What I desire to secure by Letters Patent, is—

1. In a trenching machine the combination of an endless series of rear-end-discharge digging and conveying buckets, a boom mounted to swing on an uppermost shaft in a vertical plane, for mounting said series in an endless path, a bucket cleaner pivotally supported to pass through each bucket for removing from said buckets the material carried thereby by impact therewith, and hydro-pneumatic means mounted on said boom to yieldingly resist movement of said cleaner by said impact, said means including drums having their lower ends connected to permit liquid communication from one to the other, one of said drums serving as a pump cylinder, a piston reciprocating therein, and means connecting said piston with said pivoted cleaner. 80
2. In a trenching machine the combination of an endless conveyor, a plurality of buckets carried by said endless conveyor, a boom mounted to swing on the uppermost shaft of the conveyor for supporting the latter and a bucket cleaner mounted to pass through each bucket successively for removing therefrom material by impact therewith, said cleaner being pivotally mounted upon a fixed support to normally swing into position closely adjacent the bucket bottoms, and an hydro-pneumatic mechanism mounted on said boom to yieldingly resist movement of said cleaner on its pivot away from its normal position, said mechanism including drums having their lower ends connected by at least one means for permitting liquid communication therebetween, one of said drums serving as a pump cylinder, a piston reciprocating therein, and means connecting said piston with said pivoted cleaner. 85
3. In a trenching machine the combination of an endless conveyor, a plurality of buckets carried by said endless conveyor, a boom mounted to swing on the uppermost shaft of the conveyor for supporting the latter and a bucket cleaner pivotally mounted upon a fixed support to pass through each bucket successively for removing therefrom the contents thereof by impact therewith, the path of the cleaner through each bucket being in an arc gradually receding from the path of the bottom of the bucket, and hydro-pneumatic mechanism mounted on said boom to yieldingly resist movement of the cleaner on its pivot by said impact, said mechanism including drums one of which is eccentrically mounted longitudinally within the other, the drums having a substantially common bottom and restricted communicating openings laterally between their lower ends, one of said drums serving as a pump cylinder, a piston reciprocating therein, and means connecting said piston with said pivoted cleaner intermediate its ends. 90
4. In a trenching machine the combination of an endless conveyor, a boom mounted to swing on the uppermost shaft of the conveyor for supporting the latter, a plurality of buckets carried by said conveyor, a bucket cleaner mounted to pass through each bucket successively by a sweeping action, and an hydro-pneumatic device for resisting movement of the cleaner in at least one direction and returning the cleaner to a normal position, said device including a pump mounted on said boom and an actuating connection between said pump and said bucket cleaner. 95
5. In a trenching machine the combination of a swinging digging beam, an endless series of rear-end-discharge digging and conveying buckets on said beam, the said bucket series having a common conveying shaft with the pivot shaft 100
- of said beam, an elongated bucket cleaner pivotally supported on the upper end of said beam but beneath said pivot shaft, to normally swing into position closely adjacent the bucket bottoms as the latter travel rearwardly and downwardly to empty their contents, said cleaner having its lower end curved counter-clockwise about said beam pivot, the eccentric pivoting of the cleaner and the beam directing the cleaner in a path through each bucket in an arc gradually receding from the path of the bottom of the bucket, and hydro-pneumatic means pivotally connected to said cleaner intermediate its ends to yieldingly move the cleaner on its pivot into a position nearest the bottom of the bucket, said hydro-pneumatic means including drums mounted on said beam beneath the cleaner pivot and having a substantially common bottom and a restricted communicating opening between their lower ends, one of said drums serving as a pump cylinder, a piston reciprocating therein and means connecting said piston with said pivoted cleaner. 105
6. In a trenching machine the combination of a frame, a boom mounted to swing with respect to said frame, an endless series of digging and conveying buckets mounted for longitudinal travel with respect to said boom, said buckets being adapted when at a predetermined point of said travel to tilt into dumping position, an elongated cleaner pivotally mounted on one end thereof on said boom, and adapted to present its opposite end in position to pass successively through said buckets while the latter are in dumping position, an hydro-pneumatic mechanism mounted on said boom between its ends, including a pump-cylinder and piston reciprocating therein, and means connecting said piston to said cleaner intermediate its ends, whereby the latter will be yieldingly controlled while passing through the buckets by the resistance encountered by said piston in said cylinder. 110
7. In a trenching machine the combination of a frame, a boom mounted to swing with respect to said frame, an endless series of digging and conveying buckets mounted for longitudinal travel with respect to said boom, said buckets being adapted when at a predetermined point of said travel to tilt into dumping position, an elongated cleaner pivotally mounted on one end thereof on said boom on a pivot parallel with the pivot of said boom but beneath and somewhat forward of the latter, the said cleaner having an upper extended end in position to pass successively through said buckets while the latter are in dumping position, and having its lower end curved counter-clockwise about said boom pivot to permit swinging of the upper end of the cleaner downwardly and rearwardly away from said boom pivot, an hydro-pneumatic mechanism mounted on said boom between its ends, including a pump-cylinder and piston reciprocating therein, and means connecting said piston to an intermediate point on said cleaner, whereby the latter will yieldingly resist a counterclockwise swinging movement on its pivot while the opposite end thereof passes through the buckets in their travel on said boom. 115
8. In a trenching machine, the combination of a frame, a boom mounted to swing with respect to said frame, an endless series of digging and conveying buckets mounted for longitudinal travel with respect to said boom, said buckets being adapted at a predetermined point of said travel to tilt into dumping position, an elongated cleaner pivotally mounted on one end thereof on said 120
- beam, an elongated bucket cleaner pivotally supported on the upper end of said beam but beneath said pivot shaft, to normally swing into position closely adjacent the bucket bottoms as the latter travel rearwardly and downwardly to empty their contents, said cleaner having its lower end curved counter-clockwise about said beam pivot, the eccentric pivoting of the cleaner and the beam directing the cleaner in a path through each bucket in an arc gradually receding from the path of the bottom of the bucket, and hydro-pneumatic means pivotally connected to said cleaner intermediate its ends to yieldingly move the cleaner on its pivot into a position nearest the bottom of the bucket, said hydro-pneumatic means including drums mounted on said beam beneath the cleaner pivot and having a substantially common bottom and a restricted communicating opening between their lower ends, one of said drums serving as a pump cylinder, a piston reciprocating therein and means connecting said piston with said pivoted cleaner. 125
9. In a trenching machine the combination of a frame, a boom mounted to swing with respect to said frame, an endless series of digging and conveying buckets mounted for longitudinal travel with respect to said boom, said buckets being adapted when at a predetermined point of said travel to tilt into dumping position, an elongated cleaner pivotally mounted on one end thereof on said boom on a pivot parallel with the pivot of said boom but beneath and somewhat forward of the latter, the said cleaner having an upper extended end in position to pass successively through said buckets while the latter are in dumping position, and having its lower end curved counter-clockwise about said boom pivot to permit swinging of the upper end of the cleaner downwardly and rearwardly away from said boom pivot, an hydro-pneumatic mechanism mounted on said boom between its ends, including a pump-cylinder and piston reciprocating therein, and means connecting said piston to an intermediate point on said cleaner, whereby the latter will yieldingly resist a counterclockwise swinging movement on its pivot while the opposite end thereof passes through the buckets in their travel on said boom. 130
10. In a trenching machine, the combination of a frame, a boom mounted to swing with respect to said frame, an endless series of digging and conveying buckets mounted for longitudinal travel with respect to said boom, said buckets being adapted at a predetermined point of said travel to tilt into dumping position, an elongated cleaner pivotally mounted on one end thereof on said 135
- beam, an elongated bucket cleaner pivotally supported on the upper end of said beam but beneath said pivot shaft, to normally swing into position closely adjacent the bucket bottoms as the latter travel rearwardly and downwardly to empty their contents, said cleaner having its lower end curved counter-clockwise about said beam pivot, the eccentric pivoting of the cleaner and the beam directing the cleaner in a path through each bucket in an arc gradually receding from the path of the bottom of the bucket, and hydro-pneumatic means pivotally connected to said cleaner intermediate its ends to yieldingly move the cleaner on its pivot into a position nearest the bottom of the bucket, said hydro-pneumatic means including drums mounted on said beam beneath the cleaner pivot and having a substantially common bottom and a restricted communicating opening between their lower ends, one of said drums serving as a pump cylinder, a piston reciprocating therein and means connecting said piston with said pivoted cleaner. 140
11. In a trenching machine the combination of a frame, a boom mounted to swing with respect to said frame, an endless series of digging and conveying buckets mounted for longitudinal travel with respect to said boom, said buckets being adapted at a predetermined point of said travel to tilt into dumping position, an elongated cleaner pivotally mounted on one end thereof on said 145
- beam, an elongated bucket cleaner pivotally supported on the upper end of said beam but beneath said pivot shaft, to normally swing into position closely adjacent the bucket bottoms as the latter travel rearwardly and downwardly to empty their contents, said cleaner having its lower end curved counter-clockwise about said beam pivot, the eccentric pivoting of the cleaner and the beam directing the cleaner in a path through each bucket in an arc gradually receding from the path of the bottom of the bucket, and hydro-pneumatic means pivotally connected to said cleaner intermediate its ends to yieldingly move the cleaner on its pivot into a position nearest the bottom of the bucket, said hydro-pneumatic means including drums mounted on said beam beneath the cleaner pivot and having a substantially common bottom and a restricted communicating opening between their lower ends, one of said drums serving as a pump cylinder, a piston reciprocating therein and means connecting said piston with said pivoted cleaner. 150

boom on a pivot parallel with the pivot of said boom but beneath and somewhat forward of the latter, the said cleaner having its lower end curved in an arc approximately semicircular and normally positioned about said boom pivot, and 5 extending upwardly and forwardly from said arc into a position to pass through the several buckets of the series in succession while the buckets are in dumping position, the pivot end of the cleaner being sufficiently eccentric of the boom pivot to 10 normally swing the upper end of the cleaner closely adjacent the several bucket bottoms, and when yielding by impact with the bucket contents, receding in a path diverging from the path of the buckets, and an hydro-pneumatic mechanism mounted on said boom to yieldingly resist movement of said cleaner away from its normal 80 position, said mechanism including drums having parallel axes and a restricted communicating opening between their lower ends, one of said drums serving as a pump cylinder, a piston reciprocating therein, and means connecting said piston with said pivoted cleaner. 85
